UNITED STATES PATENT OFFICE.

CARL J. SWANSON, OF GALESBURG, ILLINOIS.

DESIGN FOR A REIN-SUPPORT.

SPECIFICATION forming part of Design No. 32,322, dated March 6, 1900.

Application filed January 18, 1900. Serial No. 1,940. Term of patent 7 years.

To all whom it may concern:

Be it known that I, CARL JOHAN SWANSON, a citizen of the United States, residing at Galesburg, in the county of Knox and State of Illinois, have invented and produced a certain new and original Design for a Rein-Support; and I do declare the following to be a full, clear, and exact description of the invention, such as will enable others skilled in the art to which it appertains to make and use the same.

The invention relates to a new and original design for a rein-support; and it consists of a design of the shape and configuration shown in the accompanying drawings, in which—

Figure 1 is a perspective view of the rein-support. Fig. 2 is a top plan view of the same.

The leading feature of the design comprises the flat bar 1, having inwardly-curved sides 20 2, loops 3 at its ends and on its lower sides, and upwardly and inwardly projecting curved arms 4, which extend from the ends of said bar past the middle of its length and are spaced apart and have their ends curved in 25 opposite directions.

What I claim is—

The design for a rein-support, substantially as herein shown and described.

In testimony whereof I have hereunto set 30 my hand in presence of two subscribing witnesses:

C. J. SWANSON.

Witnesses:

EMIL F. SWANSON,
C. F. LOTGREN.
